UNITED STATES PATENT OFFICE.

ROBERT H. HASSSLER, OF INDIANAPOLIS, INDIANA.

MASSAGE MACHINE.

Application filed October 5, 1927. Serial No. 224,061.

This invention relates to a massage machine for massaging, rubbing or manipulating the scalp of the human head of the general type shown and described in my co-pending applications, Serial No. 136,421, filed September 20, 1926; Serial No. 166,414, filed February 7, 1927; and Serial No. 204,995, filed July 7, 1927.

Medical authorities recognize that massage treatment for the scalp is quite beneficial in its effects, either for restoring a diseased scalp to a healthy state or for maintaining normal nutrition. It has been found that by first stretching and loosening the scalp thoroly and then by actually lifting it from the bony portion of the skull, that a much greater supply of blood is permitted to rush to the tiny arteries which could not otherwise get a supply of blood considered adequate for beneficial results.

The principal object of the present invention is to provide a simple and desirable hand operated massage machine that is capable of stretching, loosening and lifting the scalp in a manner similar to that described in the above mentioned co-pending applications, which machine will be inexpensive to manufacture, neat and attractive in appearance.

I have found that after the scalp has been lifted in the above stated manner, that the treatment is much more effective if the scalp is held in a lifted position thruout a period of time, during which time a supply of blood is permitted to seep into the small arteries that have otherwise been deprived of nourishment, and that could not be supplied by the more common rapid alternate lifting and lowering massage movements.

Very beneficial results are obtained by alternately giving the scalp a few vigorous massage strokes and then holding the scalp in a lifted or contracted position thru a long period of time.

One of the principal features of the present invention resides in providing a massage machine that is not only capable of stretching, loosening and lifting the scalp,—as described in my above-mentioned co-pending applications,—but which, if desired, will hold the scalp in a lifted position thru as long a period of time as desired, without any further manual effort on the part of the operator after the device has once been set for this particular type of treatment.

A further feature of the invention resides in providing the machine with a device which has adjustable means adapted to fit either under the chin or back of the head, so as to assist the natural holding or gripping action of the machine for firmly maintaining the scalp in lifted position, so that one may remove one's hands entirely from the machine, and it will continue to hold the scalp in a lifted position.

Still a further feature of the invention resides in providing a machine which may be employed for giving the scalp a few vigorous massaging strokes and then be mechanically held in a locked position for the purpose of holding the scalp in a contracted or lifted position, and worn that way for a period of time, after which the massage operations and the operation of locking it in the contracted position may be repeated at intervals when desired.

A still further feature of the invention resides in providing a machine which is constructed so that the portion of the actuator means gripped by the hands, is so disposed and operated, that the pressure exerted by the hands for operating the device will simultaneously maintain a pressure on the scalp, whereby at no time during normal oscillatory movements of the actuator means, is the contact pressure on the scalp lessened.

Still another feature of the invention resides in the provision of a manually operated machine, in which the mechanism is so connected as to produce a synchronized movement of the opposed massage elements when in operation.

Another feature of the invention resides in arranging the massaging elements and attaching them to the machine so that they are capable of being easily adjusted to fit various shapes and sizes of heads.

With the foregoing and other objects in view which will appear as the description proceeds, the invention resides in the combination and the arrangement of parts and in the details of construction hereinafter described and claimed, it being understood that changes in the precise embodiment of the invention herein disclosed, may be made within the scope of what is claimed, without departing from the spirit of the invention.

The full nature of the invention will be understood from the accompanying draw.

ings and the following description and claims:

Fig. 1 is a plan view looking down upon the machine. Fig. 2 is a front elevation of the machine showing it applied to the human scalp. Fig. 3 is an end elevation showing the machine applied to the human scalp. Fig. 4 is a fragmentary sectional view illustrating a position of the actuator lever in the outward or opposite point of extreme travel, from that illustrated in Fig. 2. Fig. 5 is a fragmentary view looking down on the assembled machine with parts broken away. Fig. 6 is a perspective view 15 of the reciprocating member. Fig. 7 is a fragmentary end view of the assembled machine with parts shown in central vertical section. Fig. 8 is a side elevation of the synchronizing gear with the lever attached thereto having a portion thereof shown in 20 cross-section. Fig. 9 is a partial section taken on the line 9—9 of Fig. 4. Fig. 10 is a section taken on the line 10—10 of Fig. 2. Fig. 11 is a section taken on the line 25 11—11 of Fig. 4. Fig. 12 is a section taken on line 12—12 of Fig. 4. Fig. 13 is a side elevation of one of the synchronizing gears viewed as indicated by the line 13—13 of Fig. 8. Fig. 14 is a section taken on the 30 line 14—14 of Fig. 6. Fig. 15 is a side elevational view with parts broken away, showing the tension spring of the controlling pawl. Fig. 16 is a modified form showing the arrangement of the head strap 35 mounted so as to pass about the back of the head. Fig. 17 is a perspective view of the controlling pawl.

In the drawings 11 designates a central or stationary housing, the ends of which extend at an angle to each other, and for the best results are set at an angle of approximately 90 degrees. The central portion of the housing is formed hollow, having walls 12—12, so as to permit the assembling of 45 and enclosing therein, a portion of the driving mechanism. The lower or end portions of the housing are each provided with a pair of parallel pins or guide bars 13, which are rigidly secured thereto and adapted to extend outwardly therefrom. Projecting also from each of the end portions, and formed integral therewith, is a bracket 14, each bracket being provided with a bearing or journal 15. The housing 11 includes with the wall 11, a detachable cover which serves to more completely enclose the hollow portion between the walls, it being secured in place by means of a plurality of screws 17.

Pinion gears 18 are journaled between the 60 walls 12, and are so spaced that the teeth in the respective gears are in constant mesh with each other. Formed integral with each of the pinions 18 are levers 19, the outer portion of which are provided with 65 apertures. Connecting rods 21 are pivotally

attached to the levers 19 by means of clevis pins 22, which are inserted in the apertures.

Slidably mounted on each pair of guide bars 13, so as to freely reciprocate thereon, there is a reciprocating member 23 (see Fig. 70 6). These members are provided with a pair of cylindrical openings 24, adapted to receive the guide bars 13 so as to slide thereon. Positioned transversely of the cylindrical openings 24, there is provided an 75 aperture 25 adapted to have journaled therein, a pin 26. The pin is further inserted thru suitable openings in an end portion of the connecting rod 21.

A pair of angularly disposed spreading 80 arms 27 is carried by each of the reciprocating members 23, and in the present instance is formed integrally therewith. The said arms also extend downwardly at an angle to each other and support on the ends 85 thereof the massaging pads 28. Said massaging pads are connected by means of universal joints to the respective ends of the supporting arms 27, in the present instance, employing bald studs 29, socket members 30 90 and stud nuts 32 (as shown more clearly in Fig. 7).

To allow for variations in the size of human heads, an adjustment is provided in the form of a plurality of tapered apertures 95 31 in each of the arms 27, into any one of which the studs 29 may be inserted. A slot 33, made slightly larger in diameter than the threaded portion of the studs 29, and connecting the apertures 31, is provided so as 100 to permit the stud to slide therein when moved to releasing position.

An actuator lever 34 is fulcrumed on the bracket 14, the journal 15 being the fulcrum point of the lever movement. A journal pin 35 is inserted in the journal 15 and thru an intermediate opening in the lever 34. The upper portion of said lever is formed to receive a handle-bar 36, and the lower portion is formed into a yoke and is adapted 110 for pivotally attaching thereto one end of a connecting link 37,—employing a clevis pin 38 for a connecting medium. The opposite end of link 37 is adapted to pivotally attach to the pin 26 of the reciprocating 115 member 21.

A stop mechanism is provided in the form of a pawl 39 which is pivotally mounted at an intermediate point on the bracket 14. An upwardly extending finger 40 is provided for conveniently setting the pawl in an engaging or disengaging position. A tongue portion is formed on the free end of the pawl and is adapted to catch or engage with notches 42, provided in the connecting rod 21. A wire spring 43 is formed and anchored in such a position, at an intermediate point on the bracket 14, as to be constantly engaged in either one of grooves 44, provided in the pawl 36 adjacent the 130

pivot point, for exerting a constant spring pressure against the pawl so as to hold it in or out of engagement (see Fig. 15).

Referring to Figs. 2 and 3, the numeral 5 46 represents brackets which are secured to the outer extremities of the guide bars 13, and are held in position by means of screws 47. 48 represents a flexible strap or band adapted to fit around ones head, and which 10 is usually made of an elastic material. Both end portions of the strap are adjustably attached to the outwardly projecting portions of the brackets 46. Clamping type of fasteners or buckles 49 are employed in 15 the present instance for attaching means, the fasteners being anchored to the brackets and arranged in such a manner as to permit lacing into, and clamping therein, the end portions of the strap.

20 Referring to the modified structure shown in Fig. 16, the brackets 46 are provided with a downwardly and forwardly angular extension 50 to the end of which is secured the strap 48. This throws the upper ends of 25 the strap forwardly of the head so as to permit it to pass about the back of the head behind the ears.

In operation, the handle-bars are gripped by the hands and oscillated thru an arc, 30 approximating that illustrated in the drawings (see Fig. 2). The connecting link 37 serves to transmit the motion applied at the handles to the members 23. In applying the oscillatory movements to both sides of 35 the machine, the reciprocating members will be forced to slide on the guide bars 13 in opposite directions and in an angular path toward and away from the housing 11.

When it is desired to hold the scalp in 40 a pinched and lifted position the stop mechanism on the machine is set to automatically engage. The wing 40 is pushed over until the spring 43 snaps into one of the grooves 44, which exerts a pressure on the tongue 45 portion 41 of the pawl and causes it to bear against the notches 42 of the connecting rod 21. On the inward stroke of the massage pads the connecting rod 21 is carried in the same direction, and as the notches 42 reach 50 a predetermined inward point of travel, the pressure exerted from the spring 43, forces the tongue 41 down into the first of the several notches, thereby reacting against forces which tend to push the pads in the opposite direction and holds the scalp in 55 a lifted position. The wing 40 is pushed in the opposite direction for releasing the stop mechanism. If a tighter grip on the scalp is desired, the handles are moved inward far enough to cause the tongue on the pawl to engage in any one of the notches located on the connecting rod further toward the outer extremity.

From the foregoing description it will 60 be seen that at no time during the normal

operation of the device are the movements, or the position of the handle-bars such, that they lessen the pressure of the pads on the scalp. These handles are so positioned that adequate movement is transmitted to the 70 pads by oscillating them thru relatively short arcs of travel, the chords of which arcs are substantially horizontal, which feature is clearly illustrated in Fig. 2 of the drawings. By employing these substantial- 75 ly horizontal paths of movement of the handle-bars, the natural tendency during the operation of the device, is to force the pads more tightly against the scalp by means of a downward pressure from the hands, 80 which would not be true if the chords of said arcs were positioned in angular planes.

The meshing of the pinion gears, which are connected to the reciprocating members, results in the movement of both reciprocating members being synchronized so that their alternate approach and separation from the central housing 11 are simultaneous. Altho the reciprocating members move in angular paths, toward and away from 90 the central housing, due to the the universal mounting of the massage pads on the arms of the reciprocating members, a device is provided wherein the pads can snugly follow the contour of the scalp thruout their 95 entire path of travel.

It can also be seen that the arrangement of the pads and the novel construction of the machine is such that when the stop mechanism is put into action, the forces or 100 pressure reacting from the scalp, when in the pinched or lifted position, are such that the mechanism can be left on the head for an indefinite period of time without requiring further use of the operator's hands. To 105 assist in holding the device on the head and maintaining the scalp in a lifted or contracted position, the strap 48 has been provided as clearly illustrated in Figs 2 and 3 of the drawings. With the addition of such 110 a strap, the device is held more securely in place and permits more freedom on the part of one wearing the device for such a treatment. It has been found that the device is so self contained and its effects are so mild 115 that the time consumed in holding the scalp in the above described contracted position, can be advantageously employed in reading, writing or similar activities.

It may be further noted that one can treat 120 the scalp easily in the moring when arising and upon retiring in the evening without much loss of time. The device is light in construction, easily applied, and being manually operated, dispenses with the necessity 125 of having to make electrical connections as is the case in electric driven machines. It is compact enough and so light in weight that it can be worn on the head with comparatively little discomfort.

The invention claimed is:

1. In a massage machine, a housing having laterally extending and angularly disposed end portions, a pair of oppositely disposed reciprocating members mounted thereon, manually operated actuating levers mounted on each side of said housing adapted to reciprocate said members, laterally extending arms supported by said members, and a massaging element mounted on each of said arms.
2. A massage machine adapted to operate on the human head, comprising a housing extending downwardly on the sides of the head, a pair of movable massaging elements mounted on opposite sides of said housing in position to embrace the head, and manually operated handles connected with said housing for imparting movement to said elements, said handles being positioned on opposite sides of the head when in operation.
3. A massage machine adapted to operate upon a body having a substantially spherical surface, including a housing, a plurality of massaging elements mounted on opposite sides of said housing so as to reciprocate toward and away from each other, and a manually operated handle operatively connecting said elements and adapted to be manually reciprocated for causing said elements to be similarly reciprocated through the manual movement thereof.
4. A manually operated massage machine, having a housing, manually operated actuated levers journaled on said housing, a pair of oppositely disposed reciprocating message elements mounted on said housing, and a connecting rod attached to said actuating levers and elements, said actuating levers being adapted to impart an oppositely directed reciprocating motion to said elements through said rod.
5. A manually operated massage machine adapted to be applied to a body having a curved surface, comprising a housing, a plurality of massage elements carried by said housing, and hand operated levers for moving each of said elements simultaneously toward and away from said housing in angularly disposed planes substantially tangent to the curved surface of said body.
6. A manually-operated massage machine adapted to operate upon a body having a substantially spherical surface, including a support, a plurality of massaging elements mounted upon opposite sides of said support, a pair of operating handles mounted upon opposite sides of said support, and means connecting said operating handles with said elements for moving said elements toward each other upon said handles being moved away from each other and moving said elements away from each other upon said handles being moved toward each other, whereby said operation will cause a gripping and pinching action by said elements moving toward each other by reason of the pressure exerted in moving said handles away from each other.
7. A manually operated massage machine adapted to be applied to a body having a curved surface, comprising a housing having side portions extending at an angle to each other, a pair of reciprocating members, a plurality of massaging pads carried by said members, and hand operated levers for moving each of said members and their pads simultaneously toward and away from said housing, said reciprocating members traveling in angularly disposed planes corresponding to the angle of said portions of the housing.
8. A manually operated massage machine, a housing having laterally extending and angularly disposed end portions, manually operated actuating levers journaled on said housing, a pair of oppositely disposed reciprocating members mounted on said housing, a connecting rod attached to said actuating levers and reciprocating members, laterally extending arms supported by said members and directed at an angle to each other, a massaging element for each of said arms, said actuating lever being adapted to impart an oppositely directed reciprocating motion to said reciprocating members.
9. A manually operated massage machine, a housing having laterally extending and angularly disposed end portions, actuating levers pivotally mounted on said housing, a pair of oppositely disposed reciprocating members mounted on said housing, connecting rods attached to said actuating levers and reciprocating members, laterally extending arms supported by said members and directed at an angle to each other, a massaging element for each of said arms, and a ball and socket connection therebetween, said actuating levers being adapted to impart an oppositely directed reciprocating motion to said reciprocating members.
10. A massage machine adapted to grip the scalp substantially about the hat band area, including a housing, a plurality of massaging pads, and manually operated actuating levers, said levers connected with said housing and pads being adapted to cause said pads to simultaneously approach and separate from each other for first gripping and drawing the scalp into lifted position and then releasing the same.
11. A manually operated massage machine adapted to operate upon the human head, comprising a housing, a plurality of reciprocating massaging pads, and a pair of actuator handles for reciprocating said pads, said handles being so positioned with respect to said housing and pads as to continuously exert a pressure on the scalp by the manual operation thereof.

12. A massage machine comprising a pair of reciprocating members, means for moving each of said members simultaneously toward and away from each other, angularly extending arms mounted on said members, a massaging element for each of said arms, and means for adjustably securing said massaging elements to their respective arms in a predetermined position with respect thereto.
- 5 13. A massage machine, comprising a pair of reciprocating members, means for moving each of said members simultaneously toward and away from one another, and means for locking said reciprocating members in operated scalp gripping position for holding the massaging action.
- 10 14. In a manually operated massage machine adapted to be applied to a body having a curved surface comprising a housing, a pair of reciprocating members, a plurality 20 of massage elements carried by said members, means for reciprocating said members and their massage elements, and means for locking said reciprocating members in scalp gripping position for holding the massaging 25 action.
- 15 15. In a massage machine adapted to lift the scalp on the human head, comprising a housing, reciprocating members, massage elements mounted on said members, means for actuating said reciprocating members, and locking means for locking said members in a predetermined position for holding the scalp in a lifted position thru a period of time.
- 20 16. A massage machine comprising a pair of reciprocating members, means for moving each of said members simultaneously toward and away from one another, and a pawl and ratchet mechanism associated with said means for locking said reciprocating members in a predetermined position for holding the scalp in a lifted position thru a period of time.

In witness whereof, I have hereunto affixed my signature.

ROBERT H. HASSSLER.
